[57] CLAIM

The ornamental design for a posi-action beavertail grip safety, as shown.

DESCRIPTION

FIG. 1 is a side elevational view of a posi-action beavertail grip safety, showing my new design;

FIG. 2 is a rear elevational view of FIG. 1;

FIG. 3 is a cross-sectional view taken along line 3—3 of FIG. 2; and,

FIG. 4 is an end view of the bottom portion of FIG. 3. Surfaces not shown and portions shown in phantom lines are not part of the claimed design.
